WASHING MACHINE

Arthur H. Peters, Fort Wayne, Ind., assignor to
 Horton Manufacturing Company, Fort Wayne,
 Ind., a corporation of Indiana

Application January 13, 1932, Serial No. 586,330

16 Claims. (Cl. 68—15)

The invention relates generally to washing machines and it has for its primary object the production of a simplified yet sturdy structure which facilitates, and reduces the cost of, manufacture and assembly of such machines.

Another object is to produce a washing machine wherein the tub is secured on the supporting frame by simple and effective clamping means which avoids the use of bolts or screws extending through the tub.

Another object is to provide a washing machine in which the wringer supporting casting is mounted in a novel manner upon the supporting base whereby to obtain the requisite rigidity in the casting without the necessity for fixing the upper end thereof to the tub.

Other objects and advantages will become apparent from the following description taken in connection with the accompanying drawing which shows the preferred embodiment of the invention, and in which:

Figure 1 is a side elevational view of a washing machine embodying the features of the invention, certain portions being broken away to show the interior construction.

Fig. 2 is a plan section taken along the line 2—2 of Fig. 1.

Fig. 3 is a fragmental vertical sectional view taken along the line 3—3 of Fig. 2.

In the preferred form chosen for disclosure herein, the invention is illustrated as embodied in a domestic washing machine of the oscillating agitator type wherein the power for oscillating the agitator is transmitted through the bottom of a sheet metal tub 10 carried on a base unit 11 having a plurality of supporting legs 12 and 12^a. In the production of the machine, the base unit 11 is separately formed and assembled with its legs 12 and 12^a and the gear casing 13 secured thereto, after which the tub 10 is fixed in place on the base unit, a center post 14 is fixed within the tub 10 and a wringer supporting casting 15 is fixed to the structure on one side of the tub 10.

To facilitate assembly and reduce the material and labor costs, the base unit 11 is formed from an elongated relatively wide strip of sheet metal bent to provide an annular band 16 adapted to encircle the lower portion of the tub 10 and having the two ends of the strip bent outwardly to provide flanges 17 engageable by bolts 18 for clamping the band 16 upon the tub 10. Thus the band 16 forms, in effect, a transversely split clamping ring.

At its lower edge the band 16 has beads 19

to ornament and stiffen the same and the legs 12 are spot welded to the band. The legs 12 and 12^a are preferably formed from sheet metal, and are flanged along their edges and widened at the top to provide strength and are connected by cross braces 20 adjacent their lower ends.

To insure against relative vertical displacement of the tub 10 and base 11, provision is preferably made for mechanically interengaging the tub and base as an incident to the clamping of the band 16 upon the tub. This end is, in the present instance, attained through the provision of an outwardly projecting bead 21 on the tub adjacent its lower edge adapted to be engaged by a complementary groove 22 formed along the upper edge of the band 16. Manufacturing inaccuracies are rendered immaterial and a noiseless or non-squeaking support for the tub provided by interposing resilient means between the tub 10 and the band 16. Preferably this means comprises an annular band 23 of resilient material, preferably rubber, adapted to be put in place in encircling relation to the tub and upon the bead 21 prior to the placing of the tub in position on the base unit 11. The resilient band 23 is formed to fit over the bead 21 and by its contraction on the bead is maintained in proper position on the tub while the tub is being positioned within the clamping band 16 of the base unit. The clamping band is then contracted upon the tub by the bolts 18 so that the tub and base are firmly held together.

The gear casing 13 is positioned beneath the tub so that one end is located centrally of the base unit 11 while the other end projects beyond the side of the base unit, preferably beneath the clamping flanges 17, in which case the lower corners of the clamping band 16 are notched as at 24 (Fig. 3) to permit the upper surface of the gear casing 13 to be located above the lower edge of the clamping band 16. The projecting end of the gear casing 13 is supported by the leg 12^a bolted to the bottom of the gear casing 13 through the medium of an inturned flange 25. The leg 12^a is similar in form to the legs 12 and for purposes of symmetry this leg has its upper end bifurcated at 12^b to extend upwardly along the sides of the casing and inside of the clamping band 16. The bifurcated ends of the leg 12^a are not connected to the band 16.

The other or centrally located end of the casing is supported by a plate 26 bolted at 27 to the top of the gear casing to serve as a cover therefor and having a portion extending beyond one end of said casing. Said extending portion

is secured by bolts 28 to the clamping band 16 substantially opposite from the clamping flanges 17. Thus the gear casing is supported in proper position as a part of the base unit 11 prior to the assembly of the tub on the base unit, and a center post support 29 bolted on the upper surface of the plate 26 engages the bottom of the tub 10 as it is lowered into the clamping band 16 to initially locate the tub in the proper vertical relation to the clamping band. The center post support 29 is internally screw threaded at its upper end to receive a threaded nipple 30 formed on the flanged lower end of the center post 14, the nipple 30 being screwed loosely into position prior to the clamping of the band 16 so as to properly center the tub.

After the tub 10 has been clamped, the wringer supporting casting 15 is secured in place on the projecting end of the gear casing 13. The casting 15 is hollow and at its lower end is enlarged as at 31 with one open side so as to enclose and conceal the clamping flanges 17. As the casting 15 is drawn downwardly by bolts 32 into engagement with the upper surface of the gear casing 13, a rib or abutment 33 formed on the casting 15 engages the upper edges of the flanges 17 so as to hold the gear casing 13 against downward displacement, even though the machine is raised from the floor. When the bolts 32 are tightened, the distance between the abutment 33 and the top of the gear casing is such that the top engages the lower edge of the ring within the notch 24. Thus, movement of the gear casing relative to the ring in either direction is prevented. The point of engagement of the abutment 33 with the flanges 17 is a considerable distance above the upper surface of the casing 13 so as to impart rigidity to the casting 15 and avoid the necessity for supporting the casting adjacent to the top of the tub. After the casting 15 has been clamped in place, the assembly of the machine is completed by tightening the center post 14 and inserting casters 34 in the conventionally socketed lower ends of the legs 12 and 12a.

From the foregoing description, it will be apparent that the invention has provided a washing machine in which the parts may be easily and economically manufactured and assembled and in which the wringer supporting casting is rigidly supported without the use of bolts engaging the tub adjacent its upper edge.

I claim as my invention:

1. A washing machine comprising in combination, a tub, a base unit for supporting the tub having clamping means encircling the tub, means on said tub coacting with said clamping means to secure said tub on said unit, and an endless resilient contractile band encircling said tub and by its contraction thereon maintaining a position on said tub wherein it will be interposed and act resiliently between said tub and said clamping means.

2. A washing machine comprising a base unit having supporting legs, a tub supported on said base unit, said unit having a single clamping device with its operating means located at one side of said base unit, means on said tub coacting with said clamping device to secure said tub on said base, and a wringer supporting casting secured on said base unit in a position to conceal the operating means of said clamping device.

3. A washing machine having a tub, a base unit comprising a split annular clamping ring surrounding and clamping said tub, a gear casing fixedly connected at one end to said ring opposite

the split of said ring, said casing and said ring being relatively shiftable transversely of said ring at the other end of said casing, means supporting said other end of said casing upon said ring adjacent to said split, and legs supporting said ring.

4. A washing machine combining a tub and a supporting structure therefor comprising an open upstanding frame member having a plurality of legs fixed thereto, a gear casing adjacent the bottom of the frame and extending from the axial center thereof and having one end extending beyond one side thereof, a support extending from the inner end of said gear casing and connected to the side of said frame for supporting the centrally located end of said casing, an additional leg secured to said casing to support the projecting end of said casing, means for clamping said tub in place on said structure, and a wringer-supporting casting secured to the projecting end of said casing and having means thereon engaging the top of said frame member to prevent downward displacement of said projecting end of the casing with respect to said member.

5. A washing machine comprising in combination, a tub, a supporting structure for said tub, a gear casing positioned beneath and secured to said tub and having one end projecting beyond the side of said tub, an upstanding wringer supporting casting having its lower end positioned on and bolted down against the projecting end of said casing, and opposing abutments on said casting and supporting structure a substantial distance above the lower end of said casting and interengageable to impart rigidity to said casting.

6. A washing machine comprising, in combination, a separately assembled base unit having a transversely split ring, a plurality of legs connected to said ring to form a stable support for said ring whereby the ring is positioned in an elevated horizontal position, a tub the lower portion of which is adapted to fit within said ring, means for tightening said ring on said tub, and coacting means on said tub and said ring to prevent both upward and downward displacement of the tub with relation to the base unit.

7. A washing machine comprising, in combination, a tub, a split contractile ring encircling and clamping the lower end of said tub, means for contracting said ring, a gear casing positioned beneath said tub and extending adjacent said split, and means fixed to said casing and resting on said ring adjacent said split, said means fitting snugly against said ring on both sides of said split and enclosing said split on said contracting means.

8. A washing machine comprising, in combination, a base unit having supporting legs, a tub supported on said base unit, said unit comprising a transversely split clamping ring encircling said tub and having clamping flanges at its ends projecting radially outward therefrom, and means for drawing said flanges together to clamp the tub within the ring, and means fitting snugly against said ring on opposite sides of said split and concealing said split and said first-mentioned means.

9. A washing machine comprising, in combination, a tub, a base unit supporting said tub comprising a transversely split ring surrounding and peripherally clamping the lower portion of said tub, said ring being shaped to cooperate with the shape of the tub to provide a support against downward movement of the tub relative to the ring, resilient means positioned between the tub

and the ring, and means for clamping said ring to secure the ring and tub together.

10. A washing machine comprising, in combination, a tub, a transversely split ring encircling the tub, means for tightening said ring on said tub, a gear casing beneath the tub, a plate serving as a cover for said casing and having a portion extending beyond one end of said casing and secured to said ring, and a wringer-supporting casting having means thereon securing the other end of said casing to said ring.

11. A washing machine comprising, in combination, a tub, a transversely split ring encircling the tub, means for tightening said ring on said tub, a gear casing beneath the tub connected at one end to said ring with its other end extending beyond the tub adjacent the split, and a wringer supporting casting secured to said other end of the casing and having an abutment resting on the top of a portion of said ring, said abutment being spaced from the top of said casing a sufficient distance to bring said top of the casing into abutment with the lower edge of a portion of said ring to prevent relative vertical movement between the ring and the casing.

12. A washing machine comprising, in combination, a tub, a split ring, means for drawing the ends of said ring adjacent to the split toward each other to clamp the tub, a gear casing located beneath said tub and connected at one end to said ring at a point remote from said split, and means for securing the other end of the gear casing and the ring against relative vertical movement at a point adjacent to said split.

13. A washing machine comprising, in combination, a tub, a split ring, means for drawing the ends of said ring adjacent said split toward each other to clamp the tub, a gear casing connected at one end to said ring at a point remote from said split, and means engaging said ring

at opposite sides of said split for rigidly securing the gear casing and ring together.

14. A washing machine structure comprising a tub, and a base unit assembled in fixed relation to said tub and comprising a contractile metallic ring, the upper edge of which surrounds the lower portion of the sides of the tub and the lower portion of which projects a substantial distance below the bottom wall of the tub, a plurality of legs fixed to said lower portion of the ring and extending downwardly therefrom, means for contracting said ring about said tub to hold the tub and said base unit rigidly together, a gear casing positioned under the tub and within said lower portion of the ring and substantially concealed thereby, and means for supporting said gear casing attached to said lower portion of the ring.

15. A washing machine comprising, in combination, a tub, a split contractile supporting ring encircling and clamping the lower end of said tub, means for contracting said ring, a gear casing positioned beneath said tub, and means for supporting said casing from said ring including a part fixed to said casing and resting on said ring.

16. A washing machine structure comprising a tub, and a base unit assembled in fixed relation to said tub and comprising a contractile metallic ring, the upper edge of which surrounds the lower portion of the sides of the tub and the lower portion of which projects a substantial distance below the bottom wall of the tub, a plurality of legs fixed to said ring and extending downwardly therefrom, means for contracting said ring about said tub to hold the tub and said base unit rigidly together, a gear casing beneath said tub, and means including a supporting member extending across said ring for supporting said gear casing directly from said ring.
